ATTORNEY.

UNITED STATES PATENT OFFICE

FREDERICK H. MEYER, OF GRAND RAPIDS, MICHIGAN, ASSIGNOR TO LEITELT IRON WORKS, OF GRAND RAPIDS, MICHIGAN, A CORPORATION OF MICHIGAN

WALKWAY

Application filed June 22, 1928. Serial No. 287,581.

This invention relates to iron walkways particularly suited for dry kilns and the like.

The main objects of this invention are to provide an improved form of walkway that will be rigid and simple in construction; to provide a walkway with a foot guard along the side edges thereof; to provide strong and simple means for securing successive sections of the walkway together; and to provide an improved form of clamp for securing the walkway sections to supporting stringers.

An illustrative embodiment of this invention is shown in the accompanying drawings, in which:—

15 Fig. 1 is a fragmentary view in perspective of a section of my improved walkway secured on a supporting stringer, and the complementary end of another walkway section in spaced relation thereto preparatory 20 to joining the two sections together.

Fig. 2 is an enlarged fragmentary view in elevation of my improved form of clamp in place holding a walkway section to a supporting stringer, the stringer and walkway being 25 shown in section.

Fig. 3 is a view looking to the left in Fig. 2.

Fig. 4 is a sectional view taken on the line 4—4 of Fig. 2.

In the construction shown in the drawings, 30 the sections of walkway comprise a pair of angle bars 1 and 2 positioned in spaced parallel relation, each arranged with one flange 3 and 4 respectively in a horizontal plane and extending inwardly toward the other.

35 The other flanges 5 and 6 of the angle bars extend upwardly from the horizontal flanges, and are preferably of slightly greater width, as shown most clearly in Fig. 3.

Treads for the walkway sections are provided and comprise a plurality of relatively flat, thin rectangular shaped bars 7 placed in edgewise position in spaced parallel relation at right angles to the angle bars 1 and 2, with their ends resting upon the inwardly disposed horizontal flanges 3 and 4. The lower side edges of the treads 7 rest upon the flanges and are welded thereto at a point adjacent the outer edge of the flange, as shown at 8 in Fig. 4.

50 The ends of the treads 7 abut against the

upstanding flanges of the angle irons and are welded thereto at the upper corner of the tread as shown at 9 in Fig. 4.

The height of the upstanding flanges 5 and 6 is preferably greater than the width 55 of the treads 7 so that the flanges extend over the top plane of the treads to form foot guards along the side edges of the walkway sections.

Means are provided for coupling successive sections in end to end abutting relationship and comprise rectangular shaped connecting bars 10 and 11 welded on the outer sides of the flanges 5 and 6 respectively at one end of the walkway section. The bars 60 10 and 11 are in axial alignment with said flanges and a portion thereof protrudes beyond the ends of their respective flanges.

The opposite end of the walkway section has complementary sleeves 12 and 13 for receiving the aforementioned protruding ends of connecting bars on a similarly formed section. The sleeves 12 and 13 comprise sections of channel iron having the outer edges of their flanges welded to the outer face of 70 the upstanding flanges of the angle irons in axial alignment therewith, said channel irons thus facing in and forming rectangular shaped passageways for slidably embracing the protruding ends of the connecting bars 75 10 and 11.

Improved means are provided for securing the walkway sections to supporting stringers and comprise a clamp having a relatively flat, thin head 14 with the end portion 15 thereof bent back upon itself to form a hook. The width of the hooked head is substantially the same as the spaces between the treads 7 so that when the head is hooked over and embraces the upstanding flange 5 85 90 the portion 15 extends down the inside of the flange and snugly fits between a pair of adjacent treads as shown most clearly in Fig. 2. The head 14 is provided with a shank 16 adapted to extend down and be bent around 95 the lower edge of a supporting stringer 17 as shown at 18.

In the installation of this walkway the sections are preferably made in fifteen foot lengths, one end of each being provided with 100

the protruding connecting bars and the opposite end thereof provided with the complementary sleeves.

Successive sections are placed on the supporting stringer 17 with their adjacent ends connected in abutting relation by sliding the bars 10 and 11 into the sleeves 12 and 13 respectively of the next succeeding section.

The heads 14 of the clamp are then hooked over the supporting flanges of the angle irons, at points closely adjacent the supporting stringers and the shanks 16 are bent around the stringer to secure the clamp in place.

The two points of welding, 8 and 9, of the treads to the angle bars is such that a very rigid construction results, and the upstanding flanges of the angle bars being of greater height than the top plane of the treads 7, provide a foot guide along the side edges of the walkway.

Although but one specific embodiment of this invention has been herein shown and described, it will be understood that numerous details of the construction shown may be altered or omitted without departing from the spirit of this invention as defined by the following claims.

I claim:

1. A walkway of the character described comprising a pair of spaced parallel angle bars each arranged with one flange thereof horizontally disposed and inwardly extending, and the other flange thereof extending upwardly therefrom, and a plurality of transversely extending rectangular shaped tread bars disposed in vertical edgewise position with their ends abutting against said upwardly extending flanges and their lower side edges adjacent the ends resting upon said horizontally disposed flanges, said end and side edges being secured to said angle bars, the upwardly extending flanges of the angle bars adjacent one end thereof provided with rectangular shaped connecting members welded to the outer sides thereof in axial alignment with said flanges and with a portion thereof projecting beyond the ends of its angle bar, and the other end of said section having sleeves to receive and embrace the projecting ends of the connecting bars of an adjacent similarly formed walkway section, said sleeves being formed by welding the outer edges of a channel iron to the outer sides of the upstanding flanges of said angle bars, the upstanding flanges of the angle bars being extended at each side of the walkway above the upper edges of the tread bars to form foot guards at opposite sides of the walkway.

2. A walkway of the character described comprising a pair of spaced parallel angle bars each arranged with one flange thereof horizontally disposed and inwardly extending, and the other flange thereof extending upwardly therefrom, a plurality of transversely extending rectangular shaped tread bars disposed in vertical edgewise position with their ends abutting against said upwardly extending flanges and their lower side edges adjacent the ends resting upon said

horizontally disposed flanges, said end and side edges being secured to said angle bars, the upwardly extending flanges of the angle bars adjacent one end thereof provided with rectangular shaped connecting members welded to the outer sides thereof in axial alignment with said flanges and with a portion thereof projecting beyond the ends of its angle bar, and the other end of said section having sleeves to receive and embrace the projecting ends of the connecting bars of an adjacent similarly formed walkway section, said sleeves being formed by welding the outer edges of a channel iron to the outer sides of the upstanding flanges of said angle bars, and a clamp consisting of a relatively flat thin head of substantially the same width as the spacing between the cross bars of said walkway section, said head being folded back upon itself to form a hook adapted to embrace the upstanding flange of said angle iron and extend down the inner side thereof between the cross bars, said hooked head having a shank adapted to be bent around a supporting stringer for holding said walkway section thereon.

3. A walkway of the character described comprising a pair of spaced parallel angle bars each arranged with one flange thereof horizontally disposed and inwardly extending, and the other flange thereof extending upwardly therefrom, and a plurality of transversely extending rectangular shaped tread bars disposed in vertical edgewise position with their ends abutting against said upwardly extending flanges and their lower side edges adjacent the ends resting upon said horizontally disposed flanges, said end and side edges being secured to said angle bars, the upwardly extending flanges of the angle bars adjacent one end thereof provided with rectangular shaped connecting members welded to the outer sides thereof in axial alignment with said flanges and with a portion thereof projecting beyond the ends of its angle bar, and the other end of said section having sleeves to receive and embrace the projecting ends of the connecting bars of an adjacent similarly formed walkway section, said sleeves being formed by welding the outer edges of a channel iron to the outer sides of the upstanding flanges of said angle bars, the upstanding flanges of the angle bars being extended at each side of the walkway above the upper edges of the tread bars to form foot guards at opposite sides of the walkway.

In testimony whereof I have hereunto set my hand at Grand Rapids, Michigan, this 15th day of June, 1928.

FREDERICK H. MEYER.
